FINISHING MACHINE

William Hamann, Irondequoit, N. Y., assignor to
United Shoe Machinery Corporation, Paterson,
N. J., a corporation of New Jersey

Application November 9, 1929, Serial No. 406,133

30 Claims. (Cl. 12—78)

This invention relates to finishing machines and is illustrated as embodied in a machine for burnishing or setting edges of soles.

When sole edges are trimmed the edge at the shank portion is generally given a shape different from that given the remainder of the sole edge and, hence, when the sole edges are burnished, it is usually necessary to employ two types of burnishing tools, one adapted for engagement with the shank portion of the sole and the other adapted for engagement with the remainder of the sole edge. Accordingly, it is customary to secure one tool of each of the two types required on a carrier mounted in a tool holder which may be releasably locked in driving engagement with an oscillating drive shaft and which may be rapidly rotated through a half revolution to cause an interchange of tools by moving one from an operative to an inoperative position and moving the other into the operative position from the inoperative position.

It is a general object of this invention to provide a machine of the type referred to having improved and simplified mechanism for rotating a tool holder to cause an interchange of tools.

This result is effected in the illustrated machine by the use of improved mechanism which directly utilizes the oscillations of the shaft to impart a succession of impulses to the tool holder tending to rotate it. Accordingly, one feature of the invention consists in the provision of connections between the tool holder and the shaft having coöperating surfaces which are disposed obliquely with respect to the direction of oscillation of the shaft, together with means for yieldingly holding said surfaces in engagement. Preferably, and as herein illustrated, the oblique surface associated with the shaft is formed upon one part of a driving member fixed to the shaft, another part of which driving member and the tool holder cooperate to establish a non-turning connection therebetween when it is desired to perform a burnishing operation. Consequently, when the oblique surfaces on the tool holder and the driving member are held in engagement, the oscillation of the driving member in one direction tends to increase the pressure of the tool holder against it, while its oscillation in the other direction tends to decrease the pressure of the tool holder against it; and the frictional rotative force exerted by the driving member against the tool holder in the first-named direction is therefore substantially greater than that in the opposite direction. Moreover, the above-mentioned surfaces, being oblique to the direction of oscillation

of the shaft as herein illustrated, are also oblique to the direction of the pressure of the tool holder against the driving member. Thus, the yielding pressure of the tool holder against the driving member can be resolved into a component which tends to rotate the holder so that it moves toward the lowermost portion of the oblique surface of the driving member. Both of these tendencies aid each other and cause the rotation of the tool holder, which results in an interchange of the tools, to be started as soon as the non-turning connection between the tool holder and the driving member is interrupted and the coöperating oblique surfaces on the tool holder and the driving member are brought into engagement with each other.

In machines of this type a non-turning connection is established between the tool and the driving member by means of notches on the tool holder which are spaced in accordance with the angular distance between the tools on the tool holder, and which are shaped and arranged to receive a part of the tool holder herein termed a lug or extension. In the machine in which the present invention, as illustrated, is embodied, however, the above-mentioned notches are disposed at the extremities of the oblique surface on the driving member, which is instrumental in causing the rotation of the tool holder, or, in other words, the notches are connected by the oblique surface whereby the rotation of the tool holder will be initiated by the coaction of the oblique surfaces on the tool holder and driving member as soon as the latter are removed from non-turning engagement.

Preferably, and as herein illustrated, the tool holder is released from non-turning engagement with the driving member by the use of an operator-controlled member, constituting another feature of the invention, which is constructed and arranged to exert pressure against the tool holder so as first to move the above-mentioned lug on the tool holder from a notch in the driving member and then to move the tool holder so that the coöperating oblique surfaces on the tool holder and driving member engage each other.

It is desirable that provision be made for allowing the edge-burnishing tool in use to rotate sufficiently with respect to the holder to allow the tool to accommodate its position to changes in direction of the sole edge heightwise of the shoe. On the other hand, on account of the rapidity with which the tool-holder of a machine of the type referred to is oscillated, it is desirable to provide as tight a connection between the tool

- and its carrier as is practicable to minimize wear at the tool connection, while still providing for easy removal of the tool.
- With this in view and in accordance with a further feature of the invention, in the illustrated edge-finishing machine the tool holder is rotatably mounted and means is provided which is constructed and arranged to permit a predetermined limited rotative movement of the tool carrier relatively to the holder against yielding resistance. To this end, the illustrated tool holder is provided with yielding means arranged to engage the carrier for the edge burnishing tool to resist rotative movement of the tool. As herein shown, this means comprises a key mounted to yield toward and away from the tool carrier and arranged to engage a flat on the carrier of greater width than that of the key in order also to allow a slight axial movement of the tool.
- By the invention disclosed and claimed in application Serial No. 406,350, filed on November 11, 1929, in the name of Irving E. Booth, advantage is taken of the yielding mounting of the tool carrier above described to permit the tool to follow the sole edge, while providing an improved connection between the tool and the carrier which insures against any looseness or relative movement at that place. Considered in another aspect, the present invention provides, in combination with a tool carrier mounted for yielding axial and rotative movement, still further improved means for releasably securing a burnishing tool tightly to the tool carrier. To this end, the tool carrier of the illustrated machine has a shoulder arranged to contact with a flattened side of a tool to resist effectively rotative movement of the tool on the carrier, and a resilient latch is arranged to resist axial displacement of the tool on the carrier.
- These and other novel features of the invention are more fully pointed out in the following description and illustrated in the accompanying drawings, in which:
- Fig. 1 is a side elevation, partly in section, of an edge burnishing machine in which the present invention is embodied;
- Fig. 2 is a plan view of the machine as illustrated in Fig. 1 with parts removed;
- Fig. 3 is an enlarged section taken on the line III—III in Fig. 1;
- Fig. 4 is a section on the line IV—IV in Fig. 1; and
- Fig. 5 is a perspective view of the mechanism for initiating the rotation of the tool holder.
- A shaft 10 is rotatably mounted in a bearing 12 supported by the machine frame 14 and may be oscillated by any suitable means such, for example, as that illustrated in Letters Patent of the United States No. 1,743,480, granted January 14, 1930, in the name of E. J. Ray. On its outer end the shaft 10 carries a bushing 16 on which is rotatably mounted a tool holder 18 arranged to carry two oppositely disposed tools, which holder, by means of the mechanism described hereinafter, may be locked in non-turning relation with the shaft 10 and also may be rotated through a half revolution to cause an interchange of the tools carried by it in the manner and for the purpose well known by those skilled in this art. The locking of the tool holder 18 to the shaft 10 is effected by means of a spring 20 housed in a recess in the end of the shaft 10 and which is arranged to urge the holder 18 axially of the shaft so that opposed lugs 22 on the holder are held within complementary and diametrically opposite recesses 24

in the periphery of a driver 26 which is secured to the shaft 10 by means of a key 28. The key is retained in position by means of bolts 30 which, when tightened upon the key, lock the driver 26 securely to the shaft and prevent it from moving either about the shaft or axially thereof. The recesses 24 are formed in wear resisting liners 32 which are riveted to the periphery of the driver 26, as illustrated in Fig. 1. It will be noted from Fig. 2 that the sides of the lugs 22 which engage the sides of the liners 32 are oblique to each other and, therefore, provide a wedge fit between the holder 18 and the driver 26 when they are in the position illustrated in Fig. 2 where they are shown in locking engagement. The tension of the spring 20 which thus urges the holder 18 toward the driver 26 is transmitted thereto through an anti-friction bearing comprising a series of balls 34 interposed between a raceway 36 on the outer end of the holder 18 and a cooperating raceway 38 through which extends a flanged bushing 40 which supports one end of the spring 20 on a cross-bar 42. The other end of the spring is supported by another cross-bar 44 fixed in the shaft 10.

To initiate a half revolution of the tool holder 18 it is released from locking engagement with the driver 26 and its rotation is started by a mechanism now to be described. From one side of a housing 46, which may be attached to the frame 14 in any desired manner, extend brackets 48 in which is rotatably mounted a rock shaft 50, to the upper end of which is fixed a lever 52 and carrying at its lower end another lever 54 supporting at one extremity a pad 56 adapted to be engaged by the operator's hand or arm. The levers 52 and 54 rotatably support rolls 58 and 60 which are arranged to contact first with the chamfered faces 62 of key holders 64 fixed to the tool holder and later to be described and subsequently with oblique faces 66 on the lugs 22 of the tool holder 18. It will now be apparent that when the pad 56 is pushed to operate the levers 52 and 54 in the direction indicated by the arrow in Fig. 2 the rolls 58, 60 will be brought into engagement with the faces 62 on the key holders 64. As the pad is moved further to move the tool holder outwardly along the shaft 10, the lugs 22 are removed from locking engagement within the liners 32 and, as soon as the corners of the lugs 22 adjacent to the oblique faces 62 pass beyond the corresponding corners of the liners 32, and owing to the obliquity of the faces 62 and 66 the pressure of the rolls 58 and 60 is exerted in a direction such that one component of the pressure is utilized to impart an initial rotation to the tool holder 18 in the direction indicated by the arrow, seen in Fig. 2, carrying the faces of the lugs 22 well on to the periphery of the driver 26.

From this point the oscillation of the shaft 10 is utilized to rotate the tool holder through substantially one half a revolution, thereby to cause an interchange of the tools. The means for doing this is arranged to employ the increase in energy of the spring 20 resulting from the holder's being moved outwardly along the shaft. This means, as illustrated, comprises inclined surfaces 68, 70 on the peripheral face of the driver 26 connecting the notches in the liners 32 and, as shown in Fig. 2, the surfaces are disposed obliquely both to the direction of oscillation of the driver and to the direction of the pressure exerted against the driver by the tool holder.

As a result of this construction, each oscilla-

tion of the driver in that direction which tends to move the holder axially outwardly along the shaft owing to the obliquity of the inclined surfaces 68, 70, results in the delivery of a frictional impulse to similarly inclined surfaces 71 on the lugs 22 of the holder, tending to rotate it in the direction indicated in Fig. 2. On the other hand, during the oscillations of the driver in the other direction, the holder, in its rotation relatively to the driver 26, slides towards the lowermost portions of the inclined surfaces 68, 70 on the driver, considered longitudinally of its axis of oscillation, owing to the inertia of the holder which tends to retain it in its state of motion as indicated. It will now be apparent that, as soon as the holder is released from locking engagement with the driver and receives an initial rotation resulting from the operation of the levers 52 and 54 as hereinbefore described, the inclined surfaces of the driver 26 operate, in conjunction with the surfaces 71 of the lugs 22 on the holder urged toward the driver by the spring 20, so as to cause the initiation of a half revolution of the holder resulting in a transfer of the tool last in inoperative position to that position in which the work is presented thereto.

The edge burnishing tools are retained on pins 72, 74 projecting from the outer ends of the carriers 76, 78 which are so mounted in the tool holder 18 as to be capable of a yieldingly resisted axial and rotative movement. The illustrated carriers 76, 78 are urged outwardly of the tool holder by means of springs 80, 82 one of the ends of which bear on the tool holder and the other ends thereof being seated at the bottom of recesses in the carriers, as illustrated in Fig. 1. To allow a limited and yieldingly resisted rotative movement of the carriers with respect to the holder, each carrier has associated therewith a key 84 (Figs. 3 and 4) arranged to engage a flat 86 on each carrier and is yieldingly held in engagement therewith by means of a spring 88 which is restrained from all movement except that in a plane perpendicular to the axis of the carriers in the key holder 64. It will now be apparent from a consideration of Figs. 3 and 4 that when the carriers are rotated with respect to the holder a corner of the flat 86 will engage the key 84, rotating it in its holder about its end farthest removed from the point of contact between the carrier and the key; and when the back of the key reaches the adjacent wall of the key holder its movement is positively limited. As indicated in Fig. 3, shoulders 90, 92 of the recesses in the carriers, of which the flat 86 is the base, are separated by a distance substantially greater than the width of the key 84. Before any work is presented to the tool, the springs 80, 82 urge the respective carriers outwardly of the holder so that the shoulders 92 thereon abut a side of the key 84. In this manner outward displacement of the tools is limited. Similarly, when a piece of work is held against the tool in operative position and is urged to move the carrier inwardly of the holder, this movement of the carrier is positively limited when the shoulder 90 on the carrier engages the key 84. It will now be apparent that the same means, namely the key device above described, is constructed and arranged positively to limit both axial and rotative movements of the carrier as well as yieldingly to resist rotative movement of the carrier. Edge burnishing tools 94 having flattened sides 96, 98 are held on the ends of the carriers and are supported by the pins 72, 74 in non-turning relation with respect thereto by means of shoulders 100,

102 arranged to embrace the opposite sides of the tool. A resilient latch 104 is also supported at the outer end of each carrier and has a bent end arranged to engage within a notch on the burnishing tool, as illustrated in Fig. 1, thereby releasably to secure the tool on the carrier and to prevent its axial displacement therefrom except when removed by the operator. A finger 106 is also fixed to the end of the carrier and has a shoulder 108 arranged to engage a flat on the side of that common type of tool having a substantially cylindrical shank, thereby effectually to resist the rotation of such a tool on the carrier.

Having described my invention, what I claim as new and desire to secure by Letters Patent of the United States is:

1. In a finishing machine, in combination, an oscillating shaft, a tool holder rotatably mounted on said shaft, a driver fixed to said shaft and having an inclined face, means for releasably holding said tool holder in locking engagement with said driver, and means for moving said tool holder out of locking engagement with said driver and into engagement with its inclined face, said first-mentioned means, said driver and said holder being constructed and arranged to utilize the oscillations of said shaft in one direction to impart a succession of impulses to the holder to rotate it.
2. In a finishing machine, in combination, an oscillating shaft, a holder for a plurality of tools rotatably mounted on said shaft, said shaft and said holder having cooperating faces oblique to the direction of oscillation of the shaft, and means for holding said faces in abutting relation whereby the oscillations of the shaft in one direction are utilized to rotate the holder about the shaft thereby causing an interchange of tools.
3. In a finishing machine, in combination, an oscillating shaft, a holder for a plurality of tools rotatably mounted on said shaft, means fixed to said shaft for driving said holder, said driving means and said holder having abutting faces disposed obliquely to the direction of oscillation of the shaft, and means for holding said faces in engagement whereby the oscillations of the shaft in one direction are utilized to rotate the holder about the shaft thereby causing an interchange of tools.
4. In a finishing machine, in combination, an oscillating shaft, a holder for a plurality of tools rotatably mounted on said shaft, means for driving said holder fixed to said shaft, said driving means and said holder having abutting faces disposed obliquely to the direction of oscillation of the shaft, and means for yieldingly holding said faces together whereby the oscillations of the shaft in one direction are utilized to rotate the holder about the shaft thereby causing an interchange of tools.
5. In a finishing machine, in combination, an oscillating shaft, a tool holder rotatably mounted on said shaft, a driver fixed to said shaft having a face disposed obliquely to the direction of oscillation of the shaft, notched connections between said driver and tool holder for releasably locking them together, and means for moving said tool holder out of locking engagement with said driver and into engagement with its oblique face whereby the oscillations of said shaft in one direction are utilized to impart a succession of impulses to the holder to rotate it after it is released from locking engagement with said shaft.
6. In a finishing machine, in combination, an

- oscillating shaft, a holder for a pair of tools rotatably mounted on said shaft and having a pair of opposed extensions, driving means fixed to said shaft adapted for engagement with the extensions on said holder, notches in said driving means arranged to receive the extensions on said holder, yielding means for holding said holder and driving means in engagement, and faces on said driving means between the notches oblique to the direction of oscillation of the shaft arranged in cooperation with said yielding means to utilize the oscillation of the shaft to rotate the holder about the shaft when the holder is released from locking engagement with the driving means.
7. In a finishing machine, an oscillating shaft, a tool holder rotatably mounted on one end of said shaft and having a plurality of angularly spaced tools thereon, yielding means for urging said holder axially of said shaft to hold the shaft and the tool holder in locking engagement, means for releasing said holder from locking engagement with said shaft and for causing an increase in the potential energy of said yielding means, and means for employing said increase in energy of said yielding means and the oscillation of said shaft to cause a relative rotation of said tool holder and said shaft through the angle between successive tools on the holder.
8. In a finishing machine, an oscillating shaft, a tool holder rotatably mounted on the end of said shaft and having a plurality of angularly spaced tools thereon, yielding means for urging said holder axially of said shaft to hold them in locking engagement, operator-controlled means for releasing said holder from locking engagement with said shaft and for causing an increase in the potential energy of said yielding means, and means employing said increase in energy of said yielding means and the oscillations of said shaft to cause a relative rotation of said tool holder and said shaft through the angle between successive tools on the holder.
9. In a finishing machine, an oscillating shaft, a holder for a plurality of tools mounted for rotation on the end of said shaft whereby said tools may be brought successively into operative position, connections between said holder and said shaft comprising means for releasably locking them, and means arranged yieldingly to hold said holder and shaft in locked relation, and means for releasing said tool holder from said shaft and for initiating a rotation of the tool holder on the shaft, said connections also comprising a driving surface shaped and arranged better to utilize the oscillations of the shaft in one direction than in the other to complete the rotation of the tool holder in order to interchange the tools.
10. In a finishing machine, an oscillating shaft, a holder for a plurality of tools mounted for rotation on the end of said shaft whereby they may be successively brought into operative position, means for releasably locking said tool holder to said shaft comprising notched connections therebetween, means normally for holding said notched connections in locking engagement, means for releasing said tool holder from locking engagement with said shaft constructed and arranged to impart an initial rotation to said holder, said connections between the holder and the shaft also comprising a driving surface shaped and arranged better to utilize the oscillating motion of the shaft in one direction than in the other in order to rotate the tool holder thereby causing an interchange of the tools.
11. In a finishing machine, an oscillating shaft, a holder for a plurality of tools mounted for rotation on the end of said shaft whereby said tools may be successively brought into operative position, driving means on said shaft for causing said tool holder to oscillate therewith, resilient means for holding said tool holder releasably in locking engagement with said driving means, means for releasing said tool holder from locking engagement with said driving means and for imparting an initial rotation thereto, and means on said driving means comprising an inclined plane for utilizing the pressure of said resilient means and the oscillations of said driving means to rotate the tool holder causing an interchange of the tools.
12. In a finishing machine, a shaft, means for oscillating the shaft about its axis, a tool holder rotatably mounted on said shaft, driving means for imparting the oscillations of the shaft to the tool holder having notches in its driving surface the portions of which connecting successive notches are oblique to the direction of oscillation, an extension on said holder adapted for engagement within a notch in said driving means, a spring arranged to urge said extension on the holder within one of said notches, and means for moving the extension on said holder out of the notches and into engagement with an oblique face on said driving means.
13. In a finishing machine, a sole edge treating tool, a holder, means rotatably mounted in said holder and adapted and arranged to carry said tool at an end thereof, and means constructed and arranged yieldingly to allow a predetermined limited rotative movement of said last-mentioned means in said holder.
14. In a finishing machine, a holder, means rotatably mounted in said holder and adapted and arranged to carry a sole edge treating tool, and means constructed and arranged to resist yieldingly rotative movements of the last-mentioned means in the holder.
15. In a finishing machine, a holder, a tool carrier supported by said holder arranged for axial and rotative movement, and means for resiliently resisting rotation and for limiting the axial displacement of said carrier.
16. In a finishing machine, a tool holder having a recessed head, a spindle arranged for engagement within the recess in said holder constructed and arranged to retain a sole edge treating tool on its outer end, resilient means in said recess for urging said spindle outwardly of said holder, and connections between said holder and said spindle constructed and arranged to resist resiliently axial and rotative movements of said spindle.
17. In a finishing machine, an oscillating tool holder having a recessed head, a spindle slidably mounted in said head constructed and arranged to hold an edge treating tool at its outer end, and connections between said holder and said spindle for allowing a limited relative axial and rotative movement therebetween.
18. In a finishing machine, an oscillating tool holder having a recessed head, a tool retaining spindle mounted for limited axial and rotative movement in the recess of said head, and a spring-pressed key supported by said holder and engaging said spindle, said spindle being arranged to resist yieldingly rotation of the spindle and to limit its axial movement.

19. In a finishing machine, an oscillating tool holder having a recessed head, a tool retaining spindle slidably mounted in the recess in said head, and a key arranged to yield toward and away from the axis of said spindle, to resist rotation thereof in said holder, and also to limit the axial movement of the spindle. 5 having lugs arranged normally to be received in said notches, means for urging the tool holder into engagement with the oscillating means, and operator-controlled means for moving the tool holder so as to cause the lugs to be removed from said notches and to engage the said oblique surface on the operating means. 5
20. In a finishing machine having a tool holder arranged to allow an axial and rotative displacement of the tool, means for resiliently resisting and positively limiting axial and rotative displacements thereof. 10 27. In a finishing machine, a tool holder, an oscillating support for said holder, and means for urging said holder into engagement with said support, said support having a tool-holder-engaging surface which is oblique to the direction of pressure of the tool holder thereagainst and having notches at each end of said oblique surface to receive a part of the tool holder. 10
21. In a finishing machine having an oscillating tool holder, a spindle mounted to slide and 15 to rotate in said holder, and means comprising a yielding key arranged to engage a flat on said spindle constructed and arranged yieldingly to resist and positively to limit sliding and rotative movements of said spindle in said holder. 15
22. In a finishing machine, an oscillating tool holder having a recessed head, a tool retaining spindle mounted for limited axial and rotative movement in the recess of said head, and a spring-pressed key supported by said holder and arranged to engage a flat on said spindle thereby 20 to resist rotation of the spindle. 28. In a finishing machine, a tool holder having a lug, an oscillating support on which said holder is mounted for axial and rotative movement, yielding means for urging said holder axially into engagement with said support, said support having a tool-holder-engaging surface which is oblique to the direction of the pressure of the tool holder thereagainst and having notches at each 25 end of said surface to receive the lug on the tool holder, and operator-controlled means mounted to act upon said tool holder against the resistance of said yielding means to provide a pressure exerted in a direction such that one component of said pressure is utilized to remove the lug from a notch and the other component causes the holder to rotate whereby the lug is moved on to the oblique surface of said support. 30
23. In a finishing machine, an oscillating tool holder having a recessed head, a tool retaining spindle mounted for axial and rotative movement in the recess of said head, a flat on said spindle, and a key yieldingly supported by said holder and narrower than said flat constructed and arranged to allow but yieldingly to resist axial and rotative movements of said spindle in said head and positively to limit them. 35 29. In a finishing machine, a tool holder, means for oscillating said holder comprising an oscillating shaft on which said holder is rotatably supported and a driver fixed to said shaft for imparting its oscillations to the holder, yielding means for urging said holder against said driver, said driver having notches shaped and arranged to receive a part of the tool holder, and an annular surface connecting said notches and disposed obliquely with respect to the direction of pressure of the holder against the driver. 40
24. In a finishing machine, the combination of a tool holder, a tool carrier mounted for axial and rotative movements in said holder, means for yieldingly resisting said movements, and means for releasably securing a burnishing tool on the end of said carrier in non-turning relation comprising a resilient latch arranged to resist axial displacement of the tool on the carrier, said carrier having a shoulder arranged to contact with a flattened side of said tool effectively to resist rotative movement of the tool on the carrier. 45 30. In a finishing machine, a tool holder having a lug, means for oscillating said holder comprising an oscillating shaft on which said holder is rotatably supported and a driver having notches shaped to receive said lug and fixed to said shaft for imparting its oscillations to the holder, means for yieldingly urging said holder against said driver, said driver having an annular surface connecting its said notches and disposed obliquely with respect to the direction of pressure of the holder thereagainst, and operator-controlled means adapted to engage said lug mounted for movement in a direction oblique to the surface of the lug which it engages whereby the holder is moved into engagement with said oblique surface after it is removed from a notch in said driver. 50
25. In a finishing machine, a holder for a plurality of tools, means for oscillating the holder having a surface disposed obliquely to its direction of oscillation and shaped at its extremities to receive a part of said holder, yielding means for releasably holding said tool holder in engagement with said oscillating means, and operator-controlled means for moving the tool holder into engagement with the oblique surface of said oscillating means. 55
26. In a finishing machine, a holder for a plurality of tools, means for oscillating said holder having a surface disposed obliquely to the direction of its oscillation and having notches at the extremities of said oblique surface, said holder 60

WILLIAM HAMANN.
